[57] CLAIM

The ornamental design for a becket, as shown and described.

DESCRIPTION

FIG. 1 is a top elevational view of a becket showing my new design, the side opposite being substantially a mirror image;

FIG. 2 is a front elevational view thereof, the side opposite being substantially a mirror image;

FIG. 3 is a right side elevational view thereof; and

FIG. 4 is a left side elevational view thereof.
